UNITED STATES PATENT OFFICE

163,459

BEACH ROBE

Ruth B. Jeffrey, Miami, Fla.

Application March 18, 1949, Serial No. 1,480

Term of patent 7 years

(Cl. D3—26)

To all whom it may concern:

Be it known that I, Ruth B. Jeffrey, a citizen of the United States, residing at Miami, county of Dade, and State of Florida, have invented a new, original, and ornamental Design for a Beach Robe, of which the following is a specification, reference being had to the accompanying drawing, forming part thereof.

In the drawing:

Figure 3 is a side view of the robe looking at one of the arm holes and showing the fastener in the closed position as in Figure 1; and

Figure 4 is a sectional view taken on the line 4—4 of Figure 3 looking in the direction of the arrows and illustrating the tucks and tubular structure of the portion of the garment adjacent the arm hole.

The appearance of the garment is the same from the back as from the front.

I claim:

The ornamental design for a beach robe, substantially as shown and described.

RUTH B. JEFFREY.
